[57] CLAIM

The ornamental design for a combined toy helicopter
and ceiling fan, as shown and described.

DESCRIPTION

FIG. 1 is a side perspective view of a combined toy
helicopter and ceiling fan showing my new design;
FIG. 2 is a side elevational view thereof, the side oppo-
site being a mirror image;
FIG. 3 is a front elevational view thereof;
FIG. 4 is a rear elevational view thereof;
FIG. 5 is a top plan view thereof; and
FIG. 6 is a bottom plan view thereof.
